UNITED STATES PATENT OFFICE.

ROY RANKIN MYERS, OF TWIN FALLS, IDAHO.

PRINTING-PRESS ATTACHMENT.

1,055,212.

Specification of Letters Patent.

Patented Mar. 4, 1913.

Application filed October 24, 1911. Serial No. 656,376.

To all whom it may concern:

Be it known that I, ROY RANKIN MYERS, a citizen of the United States, and a resident of Twin Falls, in the county of Twin Falls 5 and State of Idaho, have invented certain Improvements in Printing-Press Attachments, of which the following is a specification.

My invention is an improvement in printing press attachments, and has for its object, the forming of a simple cheap, easily operated attachment of the character specified, which may be attached to existing presses with but slight changes, and by means of 15 which the forms may be tightly held and locked on the bed, without the use of the usual furniture.

In the drawings: Figure 1 is a top plan view of a type bed provided with the improvement; Fig. 2 is a section on the line 2—2 of Fig. 1; and, Fig. 3 is a bottom plan view.

As is known, with the usual printing press, the forms holding the set up type, are laid 25 upon the type bed, and are held in place by bearers on each side, clamped and wedged securely in place. The forms are of varying size, and to accommodate such forms, furniture is made use of, to fill the vacant space. 30 The placing of the furniture requires time, and the forms are not held solidly, since so many pieces are required and made use of. In the present invention, the mechanism taking the place of the furniture is immediately adjustable to any position and is a part of the machine, hence always in place, and absolutely 35 rigid, and automatic in its action. The said mechanism comprises a bar 1 of steel or like suitable material, having a plurality of 40 spaced laterally extending legs 2, four or five in number, according to the size of the press, to which it is attached. The bar lies transversely on the upper face of the type bed 3 with the legs extending longitudinally 45 of the bed. The under face of each leg 2 is provided with a series of ratchet teeth 4, extending from the free end of the leg to a point a slight distance from the junction of the leg and bar, and the teeth extend to the 50 outer end of the leg. When the forms have been placed on the type bed, the bar 1 is pressed firmly and strongly against the back sides thereof, and is locked in place by a bar 5 arranged transversely of the legs, on 55 the under face of the ink plate, and pro-

vided with teeth 6 for engaging the teeth of the legs.

The bar is operated by a rod 7, provided with a handle 8 at its outer end, and arranged substantially parallel with the legs, 60 on the under face of the bed. The rod is journaled in the ribs 12 on the under face of the bed, and the inner end of the rod is offset laterally at 9, the offset portion 9 being journaled in a bearing 10 on the ink 65 plate. The offset portion 9 is connected to the body of the rod by an inclined portion 11, and the said portion 11 is journaled in the bar 5 in a bearing 11^a. The rod is provided with an annular shoulder 13, near the 70 bar and a spring 14 encircles the rod, between the shoulder and one of the ribs 12.

A scale 15 is provided on the bar 1, for use in gaging the position of the type on the bed, and on the feed board, which is directly above the bed, a second scale is provided, which is used to gage the paper with respect to the type. The adjustment of the guides on the feed board is thus not only rapid but certain.

The rod 7 is locked from movement, by means of a latch 17, pivoted to the bed at 18, and adapted to engage a notch 19 in the rod. A pin 20 is provided for holding the latch in position. The latch holds the rod 85 with the bar in locked or unlocked position, two notches 19 being provided.

In operation, the form being placed on the bed, the bar is pushed toward the same, and is held in this position, while the slide 90 lock rod 7 is moved to engage the teeth of bar 5 firmly with the teeth of the legs. When the rod 7 moves longitudinally, the portion 11 thereof acts as a cam to move the bar 5 longitudinally of itself and transversely to 95 the legs 2. The movement is sufficient to engage or disengage each series of teeth on the bar from the teeth of the adjacent leg, thus locking the furniture bar 1 firmly in place or releasing the same. The teeth 4 and 6 are cut fine, so that a very fine adjustment is provided for. The legs move in the ribs 21 on the under face of the ink plate 22, if the ribs are of sufficient depth, and if not any suitable supporting means 105 may be provided. In the drawings, the bar is shown in half way position, with the teeth of the bar partly engaged with the teeth of the legs. The spring 14 is under compression when the rod 7 is in position 110

to unlock the bar, and thus acts to hold the parts in locked position.

The device can be applied to existing presses with but little change, and holds the 5 forms tightly in place, so that there is no possibility of accidental displacement.

I claim:

1. In combination with the type bed adapted to support forms, of a locking bar 10 for the press arranged transversely of the bed, and provided with a plurality of laterally extending legs on the opposite side from the forms, each leg having a series of ratchet teeth on its under face and facing 15 the bar, a slide bar arranged transversely of the legs and provided with a series of teeth adjacent to each leg for engaging the teeth of the legs to lock the locking bar in position and means for moving the slide bar 20 longitudinally to engage or disengage the teeth, said means comprising a rod journaled for sliding movement on the under face of the bed, said bar being provided with a handle at its outer end, and having its 25 inner end offset laterally and connected to the body of the rod by an inclined portion, the slide bar having a bearing for receiving the inclined portion, a spring normally pressing the slide bar in a direction to cause 30 the teeth on the slide bar to engage with the teeth of the legs, and means for holding the rod in adjusted position, said means comprising a latch on the bed, the rod having notches for engagement by the latch.
- 35 2. In combination with the type bed adapted to support forms, of a locking bar for the press arranged transversely of the bed, and provided with a plurality of laterally extending legs on the opposite side from the forms, each leg having a series of ratchet teeth on its under face and facing 40 the bar, a slide bar arranged transversely of the legs and provided with a series of teeth adjacent to each leg for engaging the teeth of the leg to lock the locking bar in position and means for moving the slide bar 45 longitudinally to engage or disengage the teeth, said means comprising a rod journaled for sliding movement on the under face of the bed, said bar being provided with a handle at its outer end, and having 50 its inner end offset laterally and connected to the body of the rod by an inclined portion, the slide bar having a bearing for receiving the inclined portion, a spring normally 55 pressing the slide bar in a direction

to cause the teeth on the slide bar to engage with the teeth of the legs, and means for holding the rod in adjusted position.

3. In combination with the type bed 60 adapted to support forms, of a locking bar for the press arranged transversely of the bed, and provided with a plurality of laterally extending legs on the opposite side from the forms, each leg having a series of ratchet 65 teeth on its under face and facing the bar, a slide bar arranged transversely of the legs and provided with a series of teeth adjacent to each leg for engaging the teeth of the leg to lock the locking bar in position and 70 means for moving the slide bar longitudinally to engage or disengage the teeth, said means comprising a rod slideable on the bed plate toward and from the bar, said rod having a cam at its inner end engaging the 75 bar for moving said bar longitudinally, and means for locking the rod in adjusted position.

4. In combination with the type bed 80 adapted to support forms, of a locking bar for the press arranged transversely of the bed, and provided with a plurality of laterally extending legs on the opposite side from the forms, each leg having a series of ratchet teeth on its under face and facing 85 the bar, a slide bar arranged transversely of the legs and provided with a series of teeth adjacent to each leg for engaging the teeth of the leg to lock the locking bar in position and means for moving the slide bar 90 longitudinally to engage or disengage the teeth, and means for locking the slide bar moving means in adjusted position.

5. In combination with the type bed 95 adapted to support forms, of a locking bar for the press arranged transversely of the bed, and provided with a plurality of laterally extending legs on the opposite side from the forms, and means engaging the legs for locking the bar in adjusted position, said 100 means comprising a slide bar movable transversely of the legs and provided with means for engaging each of the legs to prevent movement of the locking bar away from the form, means for moving the slide bar, and 105 means for locking the moving means in adjusted position.

ROY RANKIN MYERS.
